(57) **CLAIM**

The ornamental design for a collapsible wipes dispenser, as shown and described.

DESCRIPTION

FIG. 1 is a front perspective view of a collapsible wipes dispenser showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is an exploded perspective view thereof shown in an open configuration; and,

FIG. 9 is an exploded perspective view of the collapsible wipes dispenser shown in a collapsed configuration.

The portions shown in broken lines form no part of the claimed design.
